UNITED STATES PATENT OFFICE.

JOHN F. O'CONNOR, OF CHICAGO, ILLINOIS, ASSIGNOR TO WILLIAM H. MINER, OF CHAZY, NEW YORK.

ANTIFRICTION-BEARING.

1,209,876.

Specification of Letters Patent. Patented Dec. 26, 1916.

Application filed April 14, 1916. Serial No. 91,204.

To all whom it may concern:

Be it known that I, JOHN F. O'CONNOR, a citizen of the United States, residing at Chicago, in the county of Cook and State 5 of Illinois, have invented a certain new and useful Improvement in Antifriction-Bearings, of which the following is a full, clear, concise, and exact description, reference being had to the accompanying drawings, forming a part of this specification.

This invention relates to improvements in anti-friction bearings.

The object of this invention is to provide an anti-friction bearing and more particularly an anti-friction center bearing for railway cars of durable construction and having the elements thereof so arranged as to constantly shift the position of the anti-friction rollers and prevent excessive wear- 20 ing in spots.

In the drawing forming a part of this specification, Figure 1 is a vertical sectional view taken longitudinally of a car, showing my invention embodied in a center bearing 25 between the body and truck bolsters. Fig. 2 is a top plan view of the center bearing with the body bolster and wear plate secured thereto removed, parts being broken away to more clearly illustrate internal construction. Figs. 3 and 4 are detail sectional views taken substantially on the lines 3—3 and 4—4 respectively of Fig. 1. And Fig. 5 is a detail perspective of one of the chocks.

In said drawing, 10 denotes the body bolster of a car, 11 the truck bolster and 12 the center pin. Secured to the upper face of the truck bolster 11 is a bearing plate 13 in the form of a circular casting having four flanges 14—14 by which it is riveted 35 to the truck bolster. The bearing plate 13 is provided with an outer annular rim or flange 15, an intermediate annular rim or flange 16 and an inner annular rim or flange 17 which surrounds the central opening or 40 perforation to receive the center pin 12.

As clearly shown in Fig. 1, the flange 17 is considerably higher than the flanges 15 and 16. Secured to the under face of the body bolster 10 is another bearing plate 18 45 which may be similarly secured to the body bolster as is the plate 13 to the truck bolster. On its under face, the bearing plate 18 is

provided with an outer depending rim or flange 19 which at its lower edge is offset as indicated at 20 and thereby provides a 55 shoulder 21, the offset portion 20 overlapping slightly the rim 15. Near its center, the plate 18 is provided with another depending rim or flange 22 which overlaps the rim 17 and is recessed as indicated at 60 23 to form a shoulder between which and the upper edge of the flange 16 may be inserted a ring of fiber packing 24. A similar ring of fiber packing 25 is preferably placed between said shoulder 21 and the upper 65 edge of the flange 15.

Mounted between the opposed bearing plates 13 and 18 is the anti-friction mechanism proper which, as shown, includes an annular plate 26, preferably in the form of 70 a forging, said plate 26 being provided with an outer annular channel 27 and an inner annular channel 28 on the under side thereof. On its upper face, the plate 26 is provided with another annular channel 29 75 which is located between the channels 27 and 28. Within the annular channel 27 is located a series of spaced rollers 30, there being a chock 31 between each pair of said rollers 30. In the upper annular channel 80 29 is provided another series of rollers 32 the latter also having chocks 33 interposed between each pair thereof. In the inner annular channel 28 is provided a third series 85 of rollers 34, the latter, as shown, not having any chocks associated therewith. By referring to Fig. 3, it will be seen that the chocks 31 are provided with relatively sharp extensions 35 on the lower left hand end thereof as viewed in said figure. The right 90 hand end of each chock is rounded as indicated at 36 to correspond substantially with the periphery of the adjacent roller 30. By referring to Fig. 4, it will be noted that each of the chocks 33 is provided on its 95 lower right hand end with a relatively sharp extension 37, as viewed in said figure, the opposite end of each chock 33 being concaved as indicated at 38 to correspond with the periphery of the adjacent roller 32. 100 The height of the chocks 31 and 33 is somewhat less than the diameters of the corresponding rollers with which they coöperate.

From the preceding description, it will

be seen that movement of the rollers 30 to the right, as viewed in Fig. 3, will be prevented since said rollers will be wedged by said sharp extensions 35. Also, as appears 5 from Fig. 4, the rollers 32 will be prevented from rolling to the left, as viewed in said figure, on account of the extensions 37 on the chocks 33. The operation is as follows: For the sake of illustration, assuming the 10 truck bolster 11 and the bearing plate 13 to remain stationary while the body bolster and plate 18 rotate in a clockwise direction relatively thereto, as indicated by the arrow A in Fig. 2. During such movement, it is 15 apparent that the rollers 32 will not roll but will remain stationary due to their being chocked by the chocks 33. Therefore, the upper bearing plate 18, rollers 32, chocks 33, and intermediate plate 26 will 20 act as a unit in the clockwise rotation. This being so, the rollers 30 will roll in a clockwise direction since this movement is possible as is clear from Fig. 3. Upon return of the body bolster and bearing plate 18 25 to normal position again, that is, when it moves counter-clockwise relatively to the truck bolster 11 and bearing plate 13 thereon, the lower rolls 30 will be prevented from rotation since they will be chocked 30 by the blocks 31, and hence the bearing plate 13, rollers 30, chocks 31, and intermediate plate 26 will be relatively stationary or act as a unit. Therefore, the upper series of 35 rolls 32 will move to the right as viewed in Fig. 4, since this is possible due to the arrangement of chocks 33.

From the foregoing, it will be seen that the lower series of rollers 30 and chocks 31 will always be shifted in a clockwise direction 40 as will also the intermediate plate 26, whereas the upper series of rollers 32 and chocks 33 will always travel in a counter-clockwise direction. Therefore, there is a 45 constant shifting of the rollers relative to the respective bearing plates with which they engage and also relatively to the intermediate plate 26. This minimizes the possibility of wear as will be apparent. It will also be seen that the two upstanding annular 50 flanges 15 and 16 form a wide annular groove which is well adapted to receive and retain a lubricant for the lower rollers 30 and 34 and similarly, the channel 29 in the upper 55 face of the plate 26 forms a suitable receptacle for a lubricant for the rollers 32.

I claim:

1. In a bearing of the character described, the combination with opposed bearing plates, of two series of anti-friction members in engagement with one of said plates, another series of anti-friction members in engagement with the other of said plates, a floating plate interposed between said series of members, and chocks for said anti-friction members, the chocks for one series be-

ing arranged to limit the rotation of said anti-friction members in one direction and the chocks of the other series being arranged to limit the rotation of the anti-friction members thereof in the opposite direction. 70

2. In an anti-friction bearing of the character described, the combination with opposed relatively movable bearing plates, of two series of anti-friction members in engagement with one of said plates, another 75 series of anti-friction members in engagement with the other of said plates, and a floating plate interposed between said series of members, said interposed plate having three annular channels, one on one side and two on the opposite side and within which are disposed said series of anti-friction members. 80

3. In an anti-friction bearing of the character described, the combination with opposed relatively movable bearing plates, of two series of anti-friction members in engagement with one of said plates, another series of anti-friction members in engagement with the other of said plates, and a 85 floating plate interposed between said series of members, said interposed plate having three annular channels, one on one side and two on the opposite side and within which are disposed said series of anti-friction members, and two series of chocks associated with two of the series of anti-friction members, one series of chocks being oppositely arranged to the other. 90

4. In a center bearing for railway cars, 100 the combination with opposed bearing plates, of two annularly arranged series of anti-friction rollers in engagement with one of said plates, another series of annularly arranged anti-friction rollers in engagement 105 with the other of said plates, a floating plate interposed between said series of anti-friction rollers, and two sets of oppositely disposed chocks coöperating with two of the series of anti-friction rollers. 110

5. In an anti-friction center bearing for railway cars, the combination with two opposed plates adapted to be secured to body and truck bolsters, of a floating plate interposed between said bearing plates, said 115 floating plate having two annular channels on one side thereof and an annular channel on the opposite side, the latter being located between said two channels, and series of anti-friction members disposed in each of 120 said channels.

6. In an anti-friction center bearing for railway cars, the combination with two opposed plates adapted to be secured to body and truck bolsters, of a floating plate interposed between said bearing plates, said floating plate having two annular channels on one side thereof and an annular channel on the opposite side, the latter being located between said two channels, and series of anti- 125

friction members disposed in each of said channels, a series of chocks coöperable with the anti-friction members in said intermediate channel, and a series of chocks coöperable with the anti-friction members in the outer of said two channels, the chocks being oppositely arranged whereby the relative

positions of the anti-friction members to said bearing plates and floating plate will be constantly shifted.

10

In witness that I claim the foregoing I have hereunto subscribed my name this 17th day of March 1916.

JOHN F. O'CONNOR.
